UNITED STATES PATENT OFFICE

126,358

DESIGN FOR A FLOUR SIFTER

Freeman E. Collier, Minneapolis, Minn., assignor
to Foley Manufacturing Company, Minneapolis,
Minn., a corporation of Minnesota

Application October 7, 1940, Serial No. 95,681

Term of patent 14 years

To all whom it may concern:

Be it known that I, Freeman E. Collier, a citizen of the United States, residing at Minneapolis, in the county of Hennepin and State of Minnesota, have invented a new, original, and ornamental Design for a Flour Sifter, of which the following is a specification, reference being had to the accompanying drawing, forming part thereof, and in which:

Figure 1 is a perspective view of a flour sifter, showing my design.

Figure 2 is a top plan view thereof.

I claim:

The ornamental design for a flour sifter, substantially as shown.

FREEMAN E. COLLIER.
